UNITED STATES PATENT OFFICE

GRANVILLE S. RIDER, OF FLUSHING, NEW YORK, ASSIGNOR TO NATHAN SCHOENTHAL,
OF NEW YORK, N. Y.

DIRECTORY BOARD FOR OFFICE BUILDINGS

Application filed February 7, 1930. Serial No. 426,474.

My invention relates to directory, card or sign exhibiting structures, and its nature and advantages will be sufficiently understood from the following description of an embodiment especially adapted for use as a directory or bulletin board, for office buildings, hotels, etc.

The general object is to provide such a card exhibiting or directory structure which may have the desired attractive and decorative appearance, is at the same time of reasonably simple and economical construction, has great security against tampering by unauthorized persons, and has new and improved facilities for operation by authorized employees in inserting or readjusting the data strips or other cards.

Another object is to provide a novel and improved construction or arrangement of individual exhibiting panels in a main frame, improved means or arrangements in the individual panels for easy insertion or other manipulation of the data strips and secure retention thereof; also new and improved means of pivotally mounting the individual panels as units in the main frame.

A further object is to provide resilient means acting between the main frame or casing and the panels, and through the panels also acting on the door, when the door is unlocked or unlatched, to initially move the panels and at the same time to initially move the door toward open position, so that the door may be easily operated without necessity for an external knob or handle.

Reference is made to companion applications, Serial Nos. 426,473, 426,474, filed Feb. 7, 1930, which show generally analogous structures, and especially locking or latching and latch operating mechanisms suitable for use in the present structure, as sufficiently referred to below, but not specifically claimed herein.

The characteristics and advantages of the invention are further sufficiently explained in connection with the following detail description of the accompanying drawings, which show one representative embodiment. After considering this example, skilled persons will understand that many variations

may be made without departing from the principles disclosed and I contemplate the employment of any structures that are properly within the scope of the appended claims.

Fig. 1 is a front elevation of a card exhibiting or directory structure embodying the invention in one form.

Fig. 2 is a section at 2—2, Fig. 1, enlarged.

Fig. 3 is an enlarged detail, in side elevation, showing the pivot or hinge mounting of one of the card or directory strip holding panels.

Fig. 4 is a front elevation of the same.

Fig. 5 is a perspective view showing the parts positioned for manipulation of the cards or directory strips and also showing one card panel removed.

The main frame or casing 1 of rectangular, shallow box form, has an opening 2 to receive an inset door 3 in which a cover glass 4 is mounted. The door is hinged or pivotally mounted in the frame on hinge pins in the frame engaging in hinge lugs 5 at the top and bottom of the door frame at one side thereof, these lugs projecting outward from the frame, thus providing an offset hinge mounting so that when the door is swung open, as sufficiently shown in Fig. 5, its hinged side will swing out, clear of the adjacent side member of the main frame or casing, thus permitting full door opening with a door which is, in closed position, inset within the main frame opening, as best shown in Fig. 2.

Near the back of the frame or casing and crossing its central opening are upper and lower horizontal bars or strips 4^a and an intermediate or central strip 5^a. The door has at its free side any known or suitable locking or latching means, such for example as that disclosed in the above identified application Serial No. 426,473 and here sufficiently represented by the latch 6 engaging one of the strips 4^a or 5^a, with latch releasing means which may also be as in said application, and here sufficiently represented by aperture 7 in the door frame at its free side, this aperture being preferably shaped externally in semblance of a keyhole, although the latch operating arrangement or means is preferably, as shown in said application, incapable

of key operation, as and for reasons therein set forth.

One or preferably a plurality of card or directory slip exhibiting panels 10 are pivotally mounted within the frame opening. Each of these panels has a frame consisting of upper and lower strips 11 connected by said strips 12, and is pivotally mounted by means of hinge pins 13 carried by brackets 14 connected to the panel frame at one side and at top and bottom thereof, as best shown in Figs. 3 and 4 these hinge pins engaging in brackets 15 connected to upper and lower transverse frame strips 4^a. The side members 12 of the panel frame are provided with channel formations to receive the cards, such as the directory data strips or slips 16, and preferably in some cases, as shown, these channels 17 are formed as integral parts of thin metal strips 18 secured on frame strips 12. The upper and lower frame strips 11 have at their centers rearwardly depressed or socket formations 18a to receive the upper and lower ends of a vertical channel strip 19 which retains a cushion strip 20 of suitable compressible material such as sponge rubber. This cushion or strip is so dimensioned that it projects substantially beyond the sides of the channel strip 19, and its outer face is in a plane outward from the normal flat plane of the directory slips located in the channel 17, so that when these slips are inserted in the channels, they are bowed slightly outward and thus retained in position during insertion or adjustment. When all the panels are in closed position, that is parallel to or against the transverse strips 4^a and 5^a, and door 3 is shut and latched, the door glass 4 engages the central portions of all the directory slips or cards of all the panels and compresses all of the cushion strips 20, so that the directory slips are thereupon resiliently but firmly held in position, secure against displacement.

To assist materially in moving the various panels to convenient position for slip manipulation after the door is opened, and also to assist in door opening, as will appear, I preferably provide spring means mounted in the frame or on certain of the transverse frame strips and acting on the panels to initially move them outward when the door is opened. In the form shown, such spring means consists of strips 25 of spring sheet metal, initially bowed as shown in Fig. 5 and having their ends 26 reversely curved. These springs are fastened to the central transverse frame strip 5^a in positions opposite the side members 12 of the panels at the free sides thereof. After inserting or adjusting the directory slips, the panels are moved to nearly closed position, with their free sides in contact with the ends of springs 25, and then when the door is shut the panels are all forced back to positions parallel to the trans-

verse frame strips, with accompanying straightening and energizing of the springs 25, which are maintained in such condition by the latching or locking of the door. When the door is unlocked, the springs immediately act to force all the panels outward at their free sides and the panels in turn act on the door and force the door outward, clear of the casing at its free side, and sufficiently for the free edge of the door to be grasped, whereupon the door may be swung wide open. At the same time all the panels are moved to partly open position, so that any one of them may be easily grasped and fully opened for convenient manipulation of the directory slips.

In card exhibiting structures of this class, namely, when intended for use as building directories and the like, it is usually undesirable to provide the door with an external knob or handle, and the described construction or arrangement enables the door to be easily opened after unlocking or unlatching, without necessity for any such knob or handle.

When the structure is in closed position, as best shown in Fig. 2, the panels are all aligned in a single plane, with the free side of each panel closely abutting the next panel at its hinged side, and no space is wasted by vertical bars or stiles between the panels, since the hinge brackets 15 supporting them in the casing are parallel to the panel sides in the depthwise direction of the casing.

I claim:

1. A card exhibiting or directory structure comprising a casing having a panel opening, a panel pivotally mounted therein, the panel having card holding means, a door pivotally mounted in the casing and closing the panel opening and having a cover glass, and means for securing the door in closed position to thereby retain the panel in closed position, a spring mounted on a frame member of the casing and acting on the panel at its free side, the spring being compressed by closing of the door and acting when the door is released to move the panel and the door initially outward, the panel having a vertical cushion strip engaging behind cards or slips retained by said card holding means, the cushion strip being so dimensioned that when the door is closed it is compressed and holds the cards or slips resiliently against the door glass.

2. A card exhibiting or directory structure comprising a casing having a panel opening, a plurality of panels pivotally mounted therein to swing on vertical axes, each panel having card holding means, a door pivotally mounted in the casing and set into and closing the entire panel opening and having a cover glass, means for securing the door in closed position to thereby retain the panels in closed position, and spring means acting

between the casing and the panels and tending to move them outward and thereby acting to initially move the door outward when its securing means is released.

- 5 3. A card exhibiting or directory structure comprising a casing having a panel opening, a plurality of panels pivotally mounted therein to swing on vertical axes, each panel having card holding means, a door pivotally mounted in the casing and set into and closing the entire panel opening and having a cover glass, means for securing the door in closed position to thereby retain the panels in closed position, and springs mounted in the casing and acting on the panels at their free sides, the springs being compressed by closing of the door and acting when the door is released to move the panels and the door initially outward.
- 10 4. A card exhibiting or directory structure comprising a casing having a panel opening, a plurality of panels pivotally mounted therein to swing on vertical axes, each panel having card holding means, a door pivotally mounted in the casing and set into and closing the entire panel opening and having a cover glass, means for securing the door in closed position to thereby retain the panels in closed position, springs carried by a frame
- 15 member and engaging panels at their free sides tending to move the panels and door toward open positions, each panel having a vertical cushion strip engaging behind cards or slips retained by said card holding means,
- 20 the cushion strips being so dimensioned and arranged that when the door is closed they are compressed and hold the cards or slips resiliently against the door glass.

25 In testimony whereof I have affixed my
signature.
